BAG MAKING MACHINE

Adolph Potdevin, Garden City, N. Y., assignor to
 Potdevin Machine Company, Brooklyn, N. Y.,
 a corporation of New York

Original application March 14, 1935, Serial No.
 10,968. Divided and this application August
 20, 1936, Serial No. 96,914

4 Claims.

(Cl. 93—8)

This invention is directed to an improved method and apparatus for making bags and is particularly directed to the making of bags of the satchel bottom type from cellulose or other 5 light-weight material.

The present application is a division of my copending application Serial No. 10,968, filed March 14, 1935, Bag making machine.

Primarily the present application is directed 10 to a method and apparatus for cutting and creasing a bag tube preparatory to the formation of the bottom thereon.

In the accompanying drawings:

Fig. 1 is a sectional elevational view of the cutting and creasing mechanism for operating on the bag tube before the same reaches the bottoming drum;

Fig. 2 is a plan view of the mechanism of Fig. 1;

Fig. 3 is a sectional elevational view of improved 20 cross-scoring mechanism;

Fig. 4 is a view in part sectional elevation of mechanism which engages or grips the leading end of a bag length as the same comes up to the bottoming drum;

Fig. 5 is a part sectional elevational view of another form of cross-scoring mechanism;

Fig. 6 is an elevational view of the mechanism of Fig. 5; and

Fig. 7 is a view of a bag length after it has been 30 slit at the lip or leading end and as it appears after being scored by the scoring mechanism of Fig. 3, for instance.

Referring to the drawings in detail, the material to be handled by the present apparatus is taken from a roll in the usual fashion and fed through tubing mechanism which forms the web into a tube. The tubed material is designated 1.

The tubed material is advanced continuously and in a continuous length and is divided into bag lengths by the mechanism shown at 2. This mechanism is similar to the cutting off mechanism constituting the subject matter of Paul Hunziker copending application Serial No. 647,502. However, the cut-off mechanism may be of any 45 conventional construction. The cutting off mechanism cuts the tubing into bag lengths leaving a lip 3 at the leading end of the bag length or bag blank and a lip 4 at the trailing end. A bag length is shown in Fig. 7 where it has been 50 designated 5.

During the cutting off operation the tubing is engaged by pinch rollers 6 and 7 and lies at this time between the upper face of a plate 8 and adjustable hold-down fingers 9 carried by rods 10 secured to the machine frame.

As the tube is divided into bag lengths the leading end of each length passes between slitting and scoring mechanism shown at 11 and 12 in Fig. 1 to slit the leading end of each bag length through both walls thereof as shown at A and B in Fig. 7 for instance and to cross score the bag length as shown at CS in the same figure.

In the usual bag machine for converting ordinary bag paper into bags, it is usual to equip the machine with a cylinder having a longitudinal 10 groove therein cooperating with a scoring knife in an opposed cylinder to cross score the bag tube or bag length for the main bottom fold. Owing to the natural springiness or elasticity of materials such as "cellophane" for which my machine 15 is particularly well adapted such cross scoring mechanism fails to score the bag length satisfactorily and if, in order to obtain a well defined score with such mechanism, the parts are set closer together than when handling ordinary bag 20 paper there is always danger of cutting the material instead of scoring it with a resultant increase 25 in waste of material. The present invention provides for eliminating these difficulties.

As clearly shown on the drawings, particularly 25 Figs. 2 and 3, the scoring mechanism of this invention comprises a thin scoring blade 13 preferably mounted on a shaft 14 rotatably adjustable in discs 15 on a shaft 16. The discs 15 are adjustable circumferentially of the shaft 16, as 30 will be apparent from Fig. 2. The scoring blade 13 which depresses the bag blank or bag length out of the plane of the surface of the blank in a transverse area cooperates with a cam-and-spring operated movable jaw 17 carried by a shaft 18 35 having bearings in the end walls of a circumferentially adjustable disc cylinder 19 mounted below the discs 15 on a shaft 19'.

The cam and spring for operating the jaw 17 are designated 20 and 21, respectively. The lower 40 disc cylinder 19 carries an abutment 22 which cooperates with the movable jaw 17, the abutment and jaw constituting compression jaws. The face of the jaw 17 is cut back at an angle as seen in Fig. 3 and in operation the blade 13 depresses the 45 wall of the bag length between the jaw 17 and abutment 22 before the jaw closes and inasmuch as on continued rotation of the discs 15 and lower cylinder 19 the blade 13 is withdrawn the blade is followed up by the jaw 17 which sharply grips 50 the tucked-in portion of the bag length at the apex 23 only, as seen in Fig. 3, instead of the entire face of the jaw clamping the material between it and the abutment 22 in a manner similar 55 to that employed in clamping devices generally

used heretofore. By sharply pinching only the apex 23 of the tucked-in portion of the bag length I provide a permanent transverse or cross score CS in the material despite the natural springiness or elasticity of the same. At the same time I avoid cutting of the material so as to eliminate all waste from the cross scoring operation.

Two of the discs 15, which in addition to being adjustable circumferentially are adjustable longitudinally of the shaft 15, are provided with slitting knives 24 for slitting the bag lengths at A and B, these slitting knives as will be seen from Fig. 1 being adjustable circumferentially relatively to the shaft 16 and cooperating with the lower discs 19 which are also adjustable longitudinally of their supporting shaft 19' so as to adapt the machine for proper adjustment to slit bag lengths of different sizes, as will be understood.

The slitting operation, as will be seen from Fig. 1, precedes the cross scoring operation.

During the slitting and scoring operations the bag length underlies adjustable hold-down fingers 25 carried by vertically extending posts 26 mounted on the machine frame.

Inasmuch as there is no other operation to be performed at this point the scoring clamp 17 releases the tube immediately after the cross scoring operation is completed and the bag tube is forwarded by the rotated scoring mechanism to the next station of operation between discs 27 and cooperating lower cylinder 28, passing between hold-down fingers 25 and plate 29.

As the leading end of the bag length reaches this next station of operation the cam-and-spring operated gripper 30 carried by one of the discs 27 takes hold of the upper ply of the bag length at the point 31, Fig. 7, between the slits A clamping it against a cooperating abutment 32 on a shaft 33 on which the discs 27 are mounted.

As the bag length passes between the discs 27 and the cylinder 28 the gripper 30 will be in open position, as shown in Fig. 4, so that the nose of the gripper will enter the open end of the tube, and the projecting lip 3 on the lower wall of the tube will be pushed downwardly, as illustrated in Fig. 4, bending the same over the edge of an abutment 34 on the shaft 35 carrying the lower cylinder 28. This portion of the lower wall of the tube springing back against the back of the gripper 30 as the gripper clamps or grips the upper wall of the tube against the abutment 32. The abutment 34 is adjustable circumferentially of the shaft 5, as will be seen from Fig. 4.

Pivotedly mounted on the discs 27 is a shaft 36 carrying a blade 37. One end of this shaft 36 is equipped with a lever and cam follower roller 38 and with a suitable spring 39 to keep this roller in contact with an adjustable stationary cam 40. The function of the cam 40 is to cause the blade 37 to swing outwardly beyond the periphery of the discs 27 at the proper instant to push the scored area of the bag length away from the surface of the discs 27 and toward the large bottom opening drum 41 which carries grippers 52 for gripping the lip 3 of the bag length. In this way pulling open the bag length beyond the cross scoring CS is prevented.

The gripper 30 heretofore referred to is mounted on a shaft 42 and is controlled by a cam 43.

The hold-down fingers 25, referred to above, extend from a point at the rear of the slitting and scoring station to a point between the discs 27 and cylinder 28.

Between the scoring station and the station

just referred to I provide a rock shaft 44 carrying flat spring-like fingers 45 extending forwardly and downwardly between the hold-down fingers 25. The shaft 44 is rocked by a cam 46, cam follower 47 carried by the shaft 44 being held in engagement with this cam by a spring 48. The fingers 45 remain in a raised position during the progress of the tube 5 from the scoring station to the gripper or clamping station until the lip 3 on the leading end of the tube or bag length has been gripped by the grippers on the bottoming cylinder 41, at which time the cam 46 will be in position to move these spring fingers 45 downwardly toward the lower guide plate 29 to hold the tube or bag length with a slight spring pressure against the guide plate, the spring fingers continuing to hold the bag length in contact with this plate approximately until the gripper 30 is ready to release the leading end of the upper ply of the bag length, it being borne in mind that the leading end of the upper ply of the bag length is gripped at this time by gripper 30 as above explained.

The fingers 45, therefore, exert a slight frictional hold-back action upon the bag length during the first stages of opening the leading end of the bag length in the bottoming operation, thereby insuring that the bag length 5 will lie flat on the bottoming drum 41 so that the previously made score CS will always be in the correct position for the blade 37 to act on as previously claimed.

In Figs. 5 and 6 I have shown a modified form of cross scoring mechanism, the cross scoring blade 13' instead of being mounted on an adjustable shaft 14 is mounted in the discs 15 on the shaft 16. The cross scoring blade is adapted to be reciprocated vertically in the discs 15 by springs 105 and cam 106. The scoring jaw 17' is cam-and-spring operated and, as in the case of Fig. 2, this jaw 17' cooperates with an abutment 22'. The parts are so timed and discs 15 and 19 are so relatively positioned that as the scoring blade 13' is brought into position to engage a bag length 5 the scoring blade will be in its outermost position in the discs 15, the blade at that time riding on the high part of the cam 106. As the parts reach the position shown in Fig. 5 or on a slightly further advanced position than shown in this figure, the cross scoring blade 13' will ride off the high part of the cam 106 so as to be moved inwardly of the discs 15 by the action of the spring 105, permitting the jaw 17' to close on the material of the bag length which has been inserted between the jaw 17' and the abutment 22' by the cross scoring blade to allow the jaw to grip the apex of this depressed portion of the bag length as described in connection with my description of the apparatus shown in detail in Fig. 3. In other words, just as the cross scoring blade 13' is retracted out of the space between the jaw 17' and abutment 22' the jaw will close.

It is to be understood that the construction and operation of the bottoming mechanism constitutes no part of the present application, the same being shown, described and claimed in my co-pending application Serial No. 10,968 of which the present application is a division.

What I claim is:

1. In a bag machine, the combination of cutting-off mechanism for dividing continuously advancing bag tubing into bag lengths, hold-back mechanism following the cutting-off mechanism and cooperating therewith, slitting and cross-

scoring mechanism following the hold-back mechanism, and hold-down fingers for engaging the upper face of the bag lengths in their passage to the slitting and scoring mechanism.

5. 2. In a bag machine, cross-scoring mechanism comprising in combination a scoring blade for depressing the area of a bag blank to be scored and a pair of scoring jaws for receiving the depressed area of the blank, the active face of one 10 of said jaws being sloped away from the other jaw whereby only the apex of the depressed portion of the bag blank will be gripped by the jaws.

3. In a bag machine, cross-scoring mechanism comprising in combination a shaft extending transversely of the machine, rotatable means carrying said shaft, said rotatable means being circumferentially adjustable and said shaft being circumferentially adjustable in said rotatable means, a scoring blade carried by said shaft and 15 adapted to be carried by said rotatable means into engagement with the face of a traveling bag blank to depress the bag blank in an area extending transversely of the blank, a pair of scoring jaws, rotatable means carrying said jaws, one of 20 said jaws being pivoted, cam and spring mechanism for opening and closing said jaws, said cam and spring mechanism being so timed with re-

spect to the timing of the scoring blade that the area depressed by the blade will be gripped by said jaws, the opposed or active faces of the jaws being so shaped that only the apex of the depressed area of the bag blank will be gripped upon closure of the scorer jaws.

4. In a bag machine, cross-scoring mechanism for cross-scoring bag blanks comprising in combination scoring blade, rotatable means carrying said blade, a cam for moving said blade outwardly radially of said rotatable means, a spring for retracting said blade, a pair of scoring jaws cooperating with said scoring blade, rotatable means carrying said jaws, said scoring blade on the advance of a bag blank between said rotatable means being held in position by said cam so as to engage the bag blank to depress the same in an area extending transversely of the blank into position between said jaws, said scoring blade being retracted by said spring on further advance of the bag blank to permit said jaws to close upon the bag blank, the active face of one of said jaws sloping away from the active face of the cooperating jaw so as to apply a squeeze to the depressed portion of the bag blank which is confined to 15 the apex thereof.

ADOLPH POTDEVIN.
